UNITED STATES PATENT OFFICE.

WILLIAM D. CHASE, OF HACKENSACK, NEW JERSEY.

MECHANICAL TOY.

SPECIFICATION forming part of Letters Patent No. 400,055, dated March 26, 1889.

Application filed November 12, 1888. Serial No. 290,535. (No model.)

To all whom it may concern:

Be it known that I, WILLIAM D. CHASE, a resident of Hackensack, Bergen county, New Jersey, have invented an Improved Mechanical Toy, of which the following is a specification.

The object of my invention is to provide a mechanical toy in which the reciprocating motion of the dancer will be made irregular—
10 that is, the motion of the dancer will not be uniform, but at times will be faster than at other times.

Another object of the invention is to give a limited swinging motion to the feet of the
15 dancer.

The invention consists in the details of improvement and the combinations of parts, that are more fully hereinafter set forth.

Reference is had to the accompanying drawings, forming part of this specification, in which—

Figure 1 is a face view of a mechanical toy embodying my invention. Fig. 2 is a partly-broken back view of the same, showing the
25 mechanism for actuating the dancer; and Fig. 3 is a vertical cross-section on the plane of the line *c c*, Fig. 2.

In the accompanying drawings, the letter *A* represents a box or frame of suitable construction, which is preferably provided in front with a glass, *a*, through which the dancer or other figure to be moved may be seen, and *b* is the back of the box.

B is a partition that extends across the interior of the box or frame *A* and to which the operating mechanism of the toy is attached.

The operating mechanism of the toy consists of a suitable train of clock-work, *D*. The pallet *d* of this clock works in the teeth of the
40 escapement-wheel *e*, as in ordinary clock-movements, whereby a rotary reciprocating motion is given to the arbor *f* of the pallet *d*. To the arbor *f* of the pallet *d* is secured a crank or arm, *g*, that extends through an
45 opening, *h*, in the partition *B*. To the outer end of the crank *g* is attached a figure, *E*, which is shown in the drawings as a dancing boy, but which may be of any other desired configuration. The figure *E* is pivotally attached to the crank *g*, so that it may oscillate.

As shown in Figs. 2 and 3 of the drawings, a

pin, *i*, is passed through the figure *E* and enters a friction sleeve or tube, *j*, that is slipped over the upwardly-extending end of the crank *g*. By this means one figure may readily be 55 replaced upon the crank *g* by another; but the figure *E* may be connected with the crank *g* in any other desired manner. As the arbor *f* is reciprocated by the clock-work, the crank *g* will be moved up and down, thereby imparting an up-and-down or vertically-reciprocating motion to the figure *E*, which, being pivoted, also oscillates during said up-and-down motion. As the figure *E* is thus moved, the boy will appear to dance. In order to impart a 65 more violent oscillating motion at times to the figure, I provide a pin, *m*, that projects from the face of the partition *B*. (See Fig. 1.) This pin is placed in such a position—namely, higher than the lowest portion of the figure—
70 that the lower part or foot of the oscillating figure may at times strike it. When the figure strikes the pin *m*, as shown in dotted lines in Fig. 2, it will be thrown rather quickly off said pin, as shown in Fig. 1, by this means 75 producing a peculiar jarring or violent oscillating motion, which has the appearance of the boy moving forward and backward, as clog-dancers are known to do.

In order to give the legs *F* of the figure or 80 dancer an independent motion, I pivot said legs to the body proper, and connect the feet of the dancer by delicate springs *n* with the body proper of the figure, as at *o*. I prefer also to weight the legs of the figure, and for 85 this purpose I place weights *p* upon the feet of the figure. As the figure is now moved, the weights on the feet tend to lower them, while the springs *n* tend to raise them, thereby producing a swinging or oscillating motion of 90 the feet independent of the motion of the body.

In order to give the arbor *f*, and thereby the figure, an irregular motion, I attach to said arbor a crank or arm, *q*, which extends outwardly from said arbor, and to said crank I 95 attach a spring, *r*. To the lower end of this spring I attach a ball or weight, *s*, and in order that the spring *r* and the ball or weight *s* may have a slight independent motion, I connect said spring by cords *t* with the box *A*, 100 as shown in Fig. 2. As the arbor *f* is now reciprocated, the crank *q* will also be recipro-

cated, thereby drawing upon the spring *r*, which in turn lifts the weight *s*. The weight *s* acts to extend the spring *r*, and as these motions are repeated in quick succession the 5 spring *r* will be swung laterally, as shown in dotted lines in Fig. 2, and vibrate, thus imparting a quicker motion to the crank *q* and arbor *f* than would be imparted by the clock-work. By this means an irregular motion is 10 given to the arbor, and thereby to the dancer—that is to say, while the crank *q* is distending the spring *r* the motion of the arbor *f* will be quite uniform, but when the spring *r* swings laterally an extra impetus is given 15 to the crank *q*, which in turn imparts a quicker reciprocating motion to the figure *E*. By this means the motions of the dancer are varied, so that at times he will appear to dance with more vigor and energy than at other times, 20 thereby producing a pleasing effect.

Having now described my invention, what I claim is—

1. The combination, with a driving mechanism and a rotary reciprocating arbor, *f*, of 25 the crank *g*, connected with said arbor, and the figure *E*, pivotally connected with said crank, and the pin *m*, placed higher than the lowest portion of the figure and upon which the figure may strike to be deflected laterally, 30 substantially as described.

2. The combination of a driving mechanism having a rotary reciprocating arbor, *f*, with the laterally-extending crank *g*, having a vertical end part, figure *E*, horizontal pin *i*, for 35 supporting said figure, and sleeve *j*, carrying said pin, said sleeve embracing the vertical part of the crank *g*, substantially as described.

3. The combination, with a reciprocating figure, *E*, having jointed lower part, *F*, that 40 is supported by the figure and free to swing

on its pivot, and means, substantially as described, for reciprocating said figure, of the spring *n*, connecting the body of the figure with the pivoted extremity for regulating the swinging movement of the part *F*, substantially as described. 45

4. The combination, with a reciprocating figure having jointed lower part, *F*, pivotally suspended therefrom, and means, substantially as described, for reciprocating said figure, with the spring *n*, connecting the body of the figure with the pivoted extremity and with the weight *p*, carried by said extremity, substantially as described. 50

5. The combination, with a driving mechanism and a rotary reciprocating arbor, *f*, substantially as described, of the crank *g*, carried by said arbor, spring *r*, connected with said crank, and the weight *s*, carried by said spring, substantially as described. 60

6. The combination, with a driving mechanism and a rotary reciprocating arbor, *f*, substantially as described, of the crank *g*, carried by said arbor, spring *r*, connected to said crank, weight *s*, and cords *t*, all arranged substantially as described, whereby an irregular motion is given to the arbor *f*, substantially as specified. 65

7. The combination, with a driving mechanism and a rotary reciprocating arbor, *f*, substantially as described, of the crank *g*, carried by said arbor, and a figure, *E*, pivotally connected with said crank, and of the crank *q* and spring *r*, connected with said crank, and the weight *s* on the spring *r*, all arranged 70 for operation, substantially as described. 75
